UNITED STATES PATENT OFFICE.

ADOLPH FEINER AND THOMAS G. SAXTON, OF LEXINGTON, KENTUCKY.

DEVICE FOR HOLDING COLLARS ON SHIRTS.

SPECIFICATION forming part of Letters Patent No. 514,454, dated February 13, 1894.

Application filed May 18, 1893. Serial No. 474,699. (No model.)

To all whom it may concern:

Be it known that we, ADOLPH FEINER and THOMAS G. SAXTON, citizens of the United States, residing at Lexington, in the county 5 of Fayette and State of Kentucky, have invented certain new and useful Improvements in Devices for Holding Collars on Shirts; and we do hereby declare the following to be a full, clear, and exact description of the invention, such as will enable others skilled in the art to which it appertains to make and use the same.

Our invention relates to improvements in devices for holding collars on shirts, and for 15 kindred purposes, and it consists of certain novel features, hereinafter described and claimed.

Reference is had to the accompanying drawings, in which the same parts are indicated 20 by the same letters throughout the several views.

Figure 1 represents a perspective view of the device as completed and ready for use. Fig. 2 represents a perspective view of the 25 shirt holder and the frame connected thereto. Fig. 3 represents a perspective view of the collar holder detached from the completed device. Fig. 4 represents a perspective view of the bent lever or cam detached, and Fig. 5 represents a central transverse section of the 30 device shown in Fig. 1.

The device consists of three separable parts, the shirt holder and frame A, the spring collar holder B, and the operating lever C. The 35 combined shirt holder and frame A is provided with a downwardly projecting tongue a having wings a' adapted to slide freely downward but to catch if drawn upward. This tongue is bent over as at a³ and the interior side of the shirt holder is provided with 40 guide flanges a⁴ which terminate in the arms a⁵ and in the eyes a⁶, opposite to the shirt holding face a³. Where this plate which forms the combined frame and shirt holder 45 is curved as at a⁵, a lug a⁶ is provided as shown in Fig. 2.

a¹⁰ is groove or depression adapted to re-

ceive the end c of the operating lever C, and a¹¹ are stiffening ribs to add strength to the structure.

The collar holder B is preferably made of 50 resilient material, with two upwardly projecting arms b and b' joined together as at b⁸ and adapted to fit in the curved portion a⁵ of the frame A. The rear arm b' is provided with 55 wings b² adapted to fit on either side of the plate a³, and to slip freely downward, but to catch if drawn upward. The upper portions of these arms b and b' are broadened out as shown at b³ and b⁴, and are provided with 60 teeth b⁵ and b⁶ adapted to seize the collar when the spring B is compressed, by the operating lever C.

d⁷ represents a tongue or projection which 65 may be stamped out of the arm b for the purpose of holding the back of the necktie, but this lug may be omitted if desired.

The operating lever C is provided with a 70 handle c adapted to turn down into the groove a¹⁰, with projecting studs c' which 75 serve as trunnions or journals, and on which the lever is pivoted, and bearing face c² adapted to engage the arm b of the spring B. The parts are assembled by slipping the curved portion b⁸ of the collar holder B into the 75 curved portion a⁵ of the shirt holder and frame A, and in then bending down the ears a⁶. This holds the collar holder firmly in the frame, while the guide flanges a⁴ and b² prevent any lateral motion of the collar holder 80 in the said frame. The arms a⁵ are sprung apart sufficiently to allow the trunnions c' to be inserted into the eyes a⁶, and the device is then ready for use.

In operation the tongue a is slipped back 85 of the shirt band, or through the button hole for the collar button, the resiliency of the metal, and the wings a' and b², hold the device firmly in place, and prevent it from slipping up out of position by any ordinary motions of the wearer. The ends of the collar are then drawn between the teeth b⁵ and b⁶ 90 until the collar fits the shirt band, when the arm c of the lever C is bent down into the

groove a^{10} . This throws the arm c^2 of the lever against the front arm b of the collar holder, and presses the teeth b^5 and b^6 into the material of the collar firmly holding the same, at the same time the tabs of the collar press the arm b' back and cause the wings b^3 to nip the shirt band. Thus a double clamp is obtained, holding both the shirt and the collar, and neither can be released except by raising the lever C out of the groove c^{10} . When it is desired to release the collar, the arm c is thrown out into a position shown in Fig. 1, and the resiliency of the metal in the collar holder B will cause the teeth b^5 and b^6 to spring apart releasing the ends of the collar.

It will be seen that by the use of the herein described device the collar may be adjusted to fit the shirt band accurately, and thus the inconvenience resulting from ill-fitting collars may be avoided. It will also be seen that the device will hold collars having button holes enlarged or torn through entirely, and that it is in no way dependent upon the size of the button hole in the shirt, or upon there being any button hole there at all. This latter is of special importance, since in the ordinary methods pursued in the laundry, the starch and the chemicals used in stiffening the shirt, cause the linen fabric to rot or crystallize, and the button holes are readily cracked and broken, and therefore the use of the button-hole is if possible, to be avoided.

Again, another feature of our improved collar holding device is the fact that it will hold collars of any desired stiffness or thickness.

In the ordinary form of collar button, where the collar is very thick or is starched very stiff, and especially where the said collar is a little too short, great difficulty is experienced in inserting the collar button. This difficulty is entirely avoided by the use of our improved device.

It will be obvious that a cam or eccentric might be used in place of the bent lever C , and that many other modifications might be made, which would suggest themselves to any one skilled in the mechanic arts.

Having thus described our invention, what we claim, and desire to secure by Letters Patent of the United States, is—

1. A device for attaching collars to shirts, comprising a hook or tongue a adapted to go inside of the neck band of the shirt, and provided with wings a' sloping as shown, a frame attached to said hook, a collar holder or clamp mounted in said frame, and a device mounted in said frame for operating said collar holder or clamp, substantially as and for the purposes described.

2. A device for attaching collars to shirts, or for equivalent purposes, comprising a frame, and means for attaching said frame to the shirt, a U-shaped collar holder or clamp, made of resilient material and provided with holding teeth, mounted in said frame, and means for pressing together the sides of said

collar holder or clamp, substantially as and for the purposes described.

3. A device for attaching collars to shirts, comprising a hook adapted to go inside of the neck band of the shirt, a frame attached to said hook, provided with a recess in the front face thereof, a collar holder or clamp mounted in said frame, and a bent lever pivoted in said frame and having one arm adapted to operate said collar holder or clamp, and the other arm adapted to turn down into said recess, substantially as and for the purposes described.

4. A device for attaching collars to shirts, or for equivalent purposes, comprising a frame, provided with a recess in the front face thereof, and means for attaching said frame to the shirt, a U-shaped collar holder or clamp made of resilient material and provided with holding teeth mounted in said frame, and a bent lever pivoted in said frame and having one arm adapted to press together the sides of said collar holder or clamp, and the other arm adapted to turn down into said recess, substantially as and for the purposes described.

5. A device for attaching collars to shirts, or for equivalent purposes, comprising a combined hook and frame A provided with tongue a , wings a' , flange a^4 , and lugs a^6 , a collar holder or clamp B made of resilient material and provided with arms b and b' , wings b^2 and dentated ends, the said collar holder or clamp being mounted in said frame and held therein by said lugs a^6 , and a device mounted in said frame for pressing said arms b and b' together, substantially as and for the purposes described.

6. A device for attaching collars to shirts, or for equivalent purposes, comprising a combined hook and frame A provided with tongue a , wings a' , flange a^4 , lugs a^6 , eyes a^9 and recess a^{10} ; a collar holder or clamp B made of resilient material and provided with arms b and b' with dentated ends, the said collar holder or clamp being mounted in said frame and held therein by said lugs a^6 ; and a bent lever C provided with trunnions c' adapted to engage in said eyes a^9 , arm c adapted to enter said recess a^{10} and arm c^2 adapted to engage said arm b of the collar holder, substantially as and for the purposes described.

7. A device for attaching collars to shirts, or for equivalent purposes, comprising a frame adapted to slip over the shirt band, a U-shaped collar holder or clamp made of resilient material and provided with oppositely disposed teeth for holding the collar and with rearwardly projecting wings adapted to engage the shirt, the said collar holder being mounted in said frame, and means for pressing against the front of said U-shaped collar holder, substantially as and for the purposes described.

8. A device for attaching collars to shirts, comprising a hook adapted to go inside of the neck band of the shirt, and provided with wings a' , a frame attached to or integral with

said hook, a U-shaped collar holder or clamp made of resilient material and mounted in said frame, the said collar holder being provided with rearwardly projecting wings ^b for engaging the shirt, and oppositely disposed teeth for holding the ends of the collar, substantially as and for the purposes described.
